CLAIM

The ornamental design for a tire, as shown and de-
scribed.

DESCRIPTION

FIG. 1 is a perspective view of a tire showing my new
design, it being understood that the tread pattern is
repeated uniformly throughout the circumference of
the tire as shown schematically by solid lines;

FIG. 2 is a front elevation view thereof; and,

FIG. 3 is a side elevation view thereof, the opposite side
being a mirror image of that shown.FIG. 1

FIG. 3
